FILM VIEWING CABINET

Channing W. Gilson, Los Angeles, Calif., assignor to U.S. Industries, Inc., New York, N.Y., a corporation of Delaware

Filed Oct. 4, 1960, Ser. No. 62,367

Term of patent 14 years

(Cl. D61—1)

Fig. 3

I claim:

The ornamental design for a film viewing cabinet, substantially as shown.
